Inventor:

United States Patent Office.

JOHN B. COOK, OF LYONS, IOWA.

Letters Patent No. 77,360, dated April 28, 1868.

IMPROVED WAGON-BRAKE.

The Schedule referred to in these Letters Patent and making part of the same.

TO ALL WHOM IT MAY CONCERN:

Be it known that I, JOHN B. COOK, of Lyons, county of Clinton, and State of Iowa, have invented a new and useful Improvement in "Wagon-Brakes;" and I do hereby declare that the following is a full and exact description thereof, reference being had to the accompanying drawings, and letters of reference marked thereon, in which—

Figure 1 represents a side elevation,

Figure 2 a plan, and

Figure 3 a rear elevation of my brake.

The nature of this invention consists in the employment of a self-acting and adjustable brake, when arranged and constructed substantially in the manner hereinafter set forth.

To enable others skilled in the art to make and employ my invention, I will now describe its construction and operation.

M represents the frame, which is mounted upon the axle of the wheels F F.

Z Z designate the hounds, to which the tongue C is attached by means of a pin or rod, P.

J represents a lever, placed in a vertical position, and having as its fulcrum, at its centre, the rod or pin P. A also represents a similar lever, pivoted at its centre to the outer end of tongue C. The object of these levers will be more fully apparent hereafter.

b designates a link, by means of which one end of lever A is attached to the yoke-piece B.

H H represent the brakes, which are connected together, near their upper ends, by means of a rod or bar, said rod working in the eye-bolts u u, which are secured to the under side of frame A, as seen in the drawings.

o o designate two metal rods, secured at one of their ends to the brakes H H, and fastened at their opposite ends to the lever J, as shown in fig. 2.

Attached on either side of the tongue D, to the double-tree N, is one end of the chains L L, having their other ends secured to lever J, as clearly seen in fig. 2.

K designates a long metal rod, secured at one end to the under side of lever A, and fastened, at its opposite end, to the under side of lever J.

k k also designate two metal rods, each being connected, at one end, with the brakes H H, and fastened, at their other ends, to the lower part of lever J.

The operation of my brake is as follows: When descending a hill, the horses being checked or held back, the yoke-piece B will, consequently, be thrown back, and the lever A, which is secured to said yoke-piece by link b, will also be drawn, thus operating the rod K, which will communicate motion to lever J, and said lever will operate the rods o o and k k, and thus cause the brakes H H to press down the wheels. When it is desired to back the horses, I use a key, y, which I insert in an aperture or hole made in the double-tree and tongue, and, by means of said key, the brakes will be prevented from being operated, and the wheels left free to work.

What I claim as new, and desire to secure by Letters Patent, is—

Tongue C, yoke-piece B, lever A, rod K, chains L L and O O, lever J, brakes H H, and double-tree D, all arranged and operated as and for the purpose described.

JOHN B. COOK.
